UNITED STATES PATENT OFFICE.

CLARENCE H. MORROW, OF CLEVELAND, OHIO, ASSIGNOR TO THE HOTSTREAM HEATER COMPANY, OF CLEVELAND, OHIO, A CORPORATION OF OHIO.

THERMOSTATIC VALVE.

Application filed August 10, 1925. Serial No. 49,384.

This invention relates to thermostatic valves, such as are used for controlling the supply of gas to a water heater.

The object of the invention is to provide a simple valve mechanism which avoids the use of packed joints and therefore does away with the possibility of the valve sticking and refusing to work, in which the number of parts is reduced, and in which, nevertheless, the valve mechanism is capable of convenient adjustment from the outside to regulate the temperature at which the valve seats.

A further object of the invention is to provide a valve mechanism of the class described in which the gas chamber or chambers are sealed against the atmosphere or other pressure source by a flexible diaphragm and in which the valve is self adjusting to its seat and is not affected by lack of or improper alignment of parts.

Further objects of the invention are in part obvious and in part will appear more in detail hereinafter.

In the drawings, Fig. 1 is a side elevation of one form of valve mechanism embodying the invention; Fig. 2 is a cross section thereof on the line 2-2, Fig. 1; and Fig. 3 is a longitudinal sectional elevation on the line 3-3, Fig. 2.

The valve mechanism shown in the drawings comprises a casing including a body portion 1 provided with internally threaded members 2 and 3 at its opposite sides for connection respectively of the inlet and outlet gas supply conduits. Said member is also threaded at its outer end to receive the cap 4 and at its inner end is provided with an internally threaded skirt 5 to receive the threaded ring 6 of a sleeve 7 suitably formed, such as by the provision of the threads 8, for attachment to the tank or container for the water to be heated, said sleeve being of sufficient length to permit the attachment or assembly of the mechanism to a tank or container having a jacket of asbestos or the like, even though said jacket be of appreciable thickness. The ring 6 is connected to the body of member 7 by two or more arms 9, leaving its central portion open, as at 10, for a purpose which will appear.

In the body portion 1 of the casing is the usual cross wall 11 having a large through opening 12 controlled by a valve

13 lying in the inlet chamber 14 of the valve casing and which valve is moved toward its seat on the cross wall 11 by a compression spring 15 within the cap 4. The valve 13 has a hollow central portion with a conical bottom 16 to receive the rounded tapered end of the valve stem 17. The taper of the seat or recess 16 is greater than that of the end of the valve stem, as shown in Fig. 3, and said valve stem is slightly smaller than the recess in the valve into which it projects, enabling the valve to assume various inclined positions on the stem and thereby accommodate itself to the seat, regardless of accuracy of alignment of the parts. The valve stem is guided in a tubular guide post 18 of the body portion 1 and beyond the same passes through and is secured to the center of the flexible diaphragm 19, made of corrugated thin metal, leather or of other suitable material, and the edge of which diaphragm is clamped and tightly sealed between the ring 6 and the base of the opening in the skirt 5 of the body 1. Beyond the diaphragm the valve stem is threaded to receive a nut 20 on which is sleeved an operating member 21 having an arm terminating in a pointer 21^a and which arm is exposed in the opening 10 in member 7 for convenient manipulation by the operator's fingers. Said member 21 is rotatable on the nut 20 and is held in any position to which it may be adjusted by a set screw 21^b. Nut 20 at its inner end abuts the end of a relatively non-expansive thermostatic element, such as a carbon pencil 22, lying within a relatively expansible member, such as the copper tube 23, closed at its inner end, as at 24, and open at its outer end, where it is threaded or otherwise secured to the sleeve 7, as at 25.

With this arrangement the gas chambers are sealed against the outside air by the diaphragm 19, which diaphragm nevertheless allows free motion of the valve, valve stem and associated parts longitudinally of the mechanism according to the relative expansion between members 22 and 23 with variations in temperature of the water or other liquid into which they extend. By rotation of the nut 20 on the threaded portion of the valve stem the effective length of the inner parts from the valve to the far end of the carbon pencil may be increased or diminished, enabling the temper-

ature at which the valve seats to be readily adjusted from the outside of the mechanism and without opening the same. In practice the valve is initially set by loosening 5 the set screw 21^b and immersing the thermostatic elements 22, 23 in water of a definite temperature, say 110° Fahrenheit, which temperature is estimated to be about the mean of the range of desired adjustment. The nut 20 is then adjusted until the valve just seats, whereupon the operating member 21 is adjusted until the pointer 21^a is at a middle position upon the scale 26. Set screw 21^b is then tightened up. 10 Thereafter by moving the member 21 back and forth the temperature at which the water is maintained may be raised or lowered, the space between the arms 9 being such that the permitted motion of member 15 21 with the pitch of threads on the nut 20 gives a range of about one hundred degrees variation. The adjustment is made from the outside without disturbing any of the parts. 20 The mechanism described avoids the necessity for packed joints and nevertheless tightly seals the gas chambers and prevents escape of gas. There is no liability of any 25 of the parts sticking and regardless of accuracy in machining, the valve is self accommodating to its seat.

What I claim is:

1. Thermostatic mechanism comprising a valve body having a partition dividing it 35 into inlet and discharge chambers, said partition being provided with a gas opening and valve seat and said casing being pro-

vided with an opening in axial alignment with said valve seat, a skirt surrounding said casing opening and providing a diaphragm seat, a supporting structure comprising a sleeve, a skirt ring and connecting webs therebetween, said ring being adapted for securement to said skirt, a diaphragm located between said ring and said skirt diaphragm seat, a gas valve within said body, a thermostat mounted in the sleeve of the support and adapted for axial movement with respect to said sleeve portion, an actuating member between said thermostat and said gas valve and comprising a rod engaging the gas valve and sealed through said diaphragm, and adjustable means carried by said rod and arranged between it and said thermostatic element. 45 50 55

2. Thermostatic mechanism as in claim 1 wherein the casing is provided with a tubular guide in axial alignment with the gas valve seat for centralizing the rod and the diaphragm in assembly and the adjusting nut is provided with an arm extending to the outside of the support. 60

3. Thermostatic mechanism as in claim 1 wherein the casing is provided with a tubular guide in axial alignment with the gas valve seat for centralizing the rod and the diaphragm in assembly and the adjusting nut is provided with an arm extending to the outside of the support, and means for adjusting said arm with respect to said nut. 65 70

In testimony whereof I hereby affix my signature.

CLARENCE H. MORROW.
